Carl E. Carlsen, 867 3rd Ave., New York, N.Y.
 Substitute for abandoned application Ser. No. 92,716,
 Mar. 1, 1961. This application Sept. 10, 1962, Ser. No.
 223,293

4 Claims. (Cl. 101—125)

This application is a substitute one for the application filed Mar. 1, 1961, under Ser. No. 92,716, and abandoned, for Mimeograph Hand Printer.

This invention relates to novel improvements in hand stamps for mimeograph printing, the object of which is to make an inexpensive hand stamp which in the performance of work will fully equalize the work done by well known mimeographs.

Thus the present invention embodies all the features for circulating the ink in the stamp, and at the same time forming the basis for a larger stamp, as described in my co-pending application Ser. No. 72,667, filed November 30, 1960.

In the construction of my invention one piece of suitable material is bent upon itself approximately at the center to form two semi-cylinders adapted to receive an ink pad therebetween.

While this is a distinctive feature of novelty, it may, however be preferable to have said semi-cylinders made in two separate pieces or segments, screws or posts are then used to hold the two parts together and they are arranged so as to accommodate the fastening of the stencil on one side of the stamp.

On the other side a piece of material, or clasp, on the printing semi-cylinder is bent over the edge of the inner semi-cylinder and adapted to hold the two cylinders loosely together. This will at the same time permit the printing cylinder to move freely, as an ink storage pad is expanding and contracting under pressure.

This stamp employs in its construction some radically new features, as it actually uses two semi-cylinders, or sections one of which is perforated; it also uses two pads, one of which is of absorbent material, such as, for instance, felt, and is used for ink storage and placed between the semi-cylinders; the second pad is an ordinary mimeograph ink pad attached to the printing semi-cylinder upon which the actual stencil rests.

This stamp referred to above will be explained in detail hereinafter, as it comprises a new system for storing and distributing the ink, which constitutes the main feature of my invention.

An absorbing pad disposed between the two semi-cylinders or segments is saturated with printing ink and, as pressure is being applied to the handle for printing, the inner form part of the stamp will press upon the ink storage pad and the ink will be squeezed out through the perforations of the printing semi-cylinder and into the printing pad arranged upon the latter from where it flows to the stencil.

This system of applying pressure for ink distribution permits the user to make an innumerable amount of copies with the ink uniformly distributed on the paper, while the ink or surplus ink will return to the storage ink pad, as will be hereinafter further explained.

2

The inner segment of the two semi-cylinders, whether in one piece or separate, are each re-enforced by a bridge, which may also serve as a handle; or a separate handle may be attached thereto; this re-enforcement will make the inner segment of the stamp sturdy and firm contrary to the outer semi-cylinder which must be flexible and vibratory; thus the outer printing semi-cylinder will have a hinge-like springy movement due to the squeezing of the storage pad, as pressure is applied to the handle when rolling the stamp over the paper.

Between the inner and outer segment is a space adapted to receive an ink storage pad therebetween, while the printing pad is securely attached to the outside of the perforated printing cylinder, and the ink will thus pass freely through it from one pad to the other.

When ink is circulated and distributed under pressure it provides a cleaner stamp because it makes it unnecessary to apply so much ink so it would flow freely by itself.

The pressure on the handle will hasten or slow the flow of ink as the user controls the pressure and adjusts it accordingly; therefore, when a stamp has been newly inked very little pressure is needed for printing, except to make larger quantities of copies, when a greater amount of pressure would be required. However, all the copies would be uniformly inked as the user slowly increases the pressure.

The stamp is used by rolling it towards or away from you, and only once over the paper; as it is then lifted and returned to repeat the operation. The stamp may be used to print on a regular memo pad or any block of paper, or even a book, but the best result would be obtained if the stamp is used together with a printing base as shown in connection with this stamp.

This printing base has a right angular guide for the stamp and lines marked to guide the paper and it will assist the user to print straight and will at the same time provide a flexible or electric cushion for the stamp.

If the printing base would be provided with a soft padding, such as for instance rubber, it would facilitate making a print of high quality, similar to that of mimeographing machines, which are using a revolving perforated drum against a rubber roller.

The printing cylinder is made of less width than the inner semi-cylinder.

The two pads are extending outside of the printing semi-cylinder in order to prevent this cylinder from bruising the stencil, and the stencil extends outside of the pads to prevent any ink from getting onto the paper on the sides, but it is about even with the inner stamp. The top of the stencil is attached to prongs or screws on the inside of the stamp; the stencil is stretched tight over the printing cylinder and is folded over the sharp edge of the printing cylinder with a crease formed on said stencil so that it may fold over the said cylinder, further both corners are folded to make sure that the stencil will remain attached.

The two pads extend beyond and completely enclose the sides of the printing semi-cylinder; this is an essential feature to prevent the printing semi-cylinder from damaging the stencil.

As this stamp is always rolled in one direction and the ink is forced in the same direction, the two ink pads

member, whereby to prevent said outer member from damaging the stencil and soiling the paper.

3. In a hand stamp, as claimed in claim 1, and wherein the stencil being re-enforced at each end on the side contacting the paper to be printed, whereby to prevent the 5 color of the stencil from smudging the paper as the stamp is started or lifted off the paper.

4. In a hand stamp, as claimed in claim 1, and wherein the stencil at the finishing end is having a strip of paper, 10 whereby to absorb escaping ink.
